UNITED STATES PATENT OFFICE.

LOUIS FRIEDMAN, OF NEW YORK, N. Y.

MULTICOLOR-PRESS.

1,396,827.

Specification of Letters Patent. Patented Nov. 15, 1921.

Application filed September 16, 1920. Serial No. 410,630.

To all whom it may concern:

Be it known that I, LOUIS FRIEDMAN, a citizen of the United States, residing at New York city, borough of Manhattan, in the 5 county and State of New York, have invented a certain new and useful Multicolor-Press, of which the following is a specification.

This invention relates to improvements in 10 multi-color presses, and embodies, more particularly, a construction which is adapted to be used on or in connection with ordinary job printing presses, which enable printing to be expeditiously turned out in colors.

15 Heretofore, multi-color presses have been rather complex, expensive structures, and, for these reasons, have not been available to ordinary job printers. The present invention, however, because of its simplicity and 20 efficiency in operation, its ease of attachment to ordinary job printing presses, and its economy in manufacture, renders it of special commercial value in its intended field of use.

Various features of the invention, as well 25 as their functions and advantages, will be apparent from the hereinafter detailed description read in conjunction with the accompanying drawings.

30 The accompanying drawings illustrate one practical embodiment of the invention, but the construction therein shown is to be understood as illustrative, only, and not as defining the limits of the invention.

Referring to the drawings, Figure 1 is a 35 plan view of the invention.

Fig. 2 is a front elevation thereof.

Fig. 3 is an underneath plan view of one of the inking plates.

40 Fig. 4 is a similar view of another of such plates.

Fig. 5 is a section on the line 5—5 of Fig. 2.

Fig. 6 is a sectional elevation on the line 6—6 of Fig. 2; and,

45 Fig. 7 is a section through one of the plate supporting posts.

Referring to the drawings, 1 designates a plate supporting bar of an ordinary job printing press. This bar is provided with 50 a socket 2 in which is usually adapted to fit the spindle of a large ink plate from which ink is supplied through a form roller 3 to the form or type of the press.

In carrying out the present invention, the 55 single large inking plate is removed and in lieu thereof, a plurality of smaller plates 4

are employed, all of which smaller plates are organized as a unit so as to be readily placed in position on the press, after the removal of the single plate usually employed. To this 60 end, a yoke 5 is provided, which has a depending stem or arbor 6 adapted to seat into the socket 2 of the supporting bar 1, while the upstanding legs of the yoke 5 are rigidly secured by means of screws 7 to a beam 8. 65 On this beam 8 are mounted the several ink plates 4 in such manner that they may be slid longitudinally of the bar 8 as may be desired.

Each plate 4 is supported on the bar 8 by 70 means of a post 9, which, as shown in cross section in Fig. 7, is provided with a passage 10 through which the bar 8 is adapted to extend, a further passage 11 through which an operating shaft 12 may be passed and a 75 socket 13 into which seats an arbor 14, one of which depends from the center of each inking plate 4 as shown best in Figs. 3 and 4. In this manner, the several inking plates are supported on the bar 8, but may be slid 80 longitudinally of the bar so as to ink the proper portion of the form roll 3 in accordance with the placement of the type in the form to correspond with the colors desired. The plates, however, may be locked in place 85 by means of set screws 15, one of which is associated with each post 9.

It will be noted that each plate is mounted for rotation on its respective post, while the bar 8 is mounted for rotation on the part 1 90 of the press. The bar 8 is, however, normally locked against rotation with reference to the press by any suitable means such as a set screw (not shown) which may be threaded through the part 1 and engage with the 95 side of the arbor 6.

For the proper functioning of the press, and more particularly for the proper distribution of the ink, the plates 4 should be revolved and this may be accomplished by 100 gearing all of the parts together and driving any one of them. In the showing made, I form on the inner side of each plate an annular rack 16 adapted to coöperate with a gear 17, fixed on the operating shaft 12. As 105 stated, the operating shaft is journaled in the passages 11 of the posts 9, and each gear is secured to this shaft by a set screw so that when one of the plates is rotated, all will be simultaneously rotated. I find it convenient 110 to drive the plates from one of the end plates by forming on the under side thereof,

an annular series of ratchet teeth 18 as shown best in Figs. 2 and 3 and with these ratchet teeth is associated a ratchet 19, which may be operated, from any suitable 5 moving part of the press to impart to the ratchet, toothed plate 4, a step by step rotary movement, which will be transmitted through the racks and gears and through the shaft 12 to the other plates so that they 10 will all be turned in unison, for the purpose of properly distributing the ink.

It will be noted that the plates 4 are arranged in diagonal relation with reference to the travel of the form roller 3 and this is 15 the preferable arrangement since the plates 4 are smaller in diameter than the single plate usually employed and it is desirable that the form roller should have bearing on one of the plates, at least during its ink receiving travel. By employing this arrangement, such bearing surface is provided and proper operation of the form roller is assured.

A distinct advantage of the present invention resides in the fact that through its employment, an ordinary job press which has heretofore been capable of printing only one color at a time is rendered capable of printing in a plurality of colors without necessitating a reorganization of the press and enabling it to be readily reconverted into a single color press with a single ink plate as originally employed if desired. The present invention may be employed in this manner 30 in the nature of an attachment, although, if desired, the novel features of this invention may be availed of in press construction for the manufacture of a permanent multi-color press.

Having thus fully described the invention, what I claim as new and desire to secure by Letters Patent is:

1. A multi-color printing press embodying a form roller, a plurality of ink plates 45 mounted on fixed axes in the path of the form roller and positioned at spaced distances apart in oblique relation to the direc-

tion of travel of the form roller so as to form a support for the form roller during its entire travel over the ink plates in succession, each of said plates being adapted to contain ink of a predetermined color, whereby different portions of the length of the form roller receive ink of a corresponding color from the coöperating plates. 50

2. A multi-color printing press embodying a form roller, a plurality of ink plates arranged in the path of the form roller and positioned at spaced distances apart in oblique relation to the direction of travel 60 of the form roller so as to form a support for the form roller during its entire travel over the ink plates in succession, each of said plates being adapted to contain ink of a predetermined color, whereby different 65 portions of the length of the form roller receive ink of a corresponding color from the coöperating plates, a planetary gear associated with each plate, an operating shaft provided with gears meshing with the planetary 70 gears of the respective plates and ratchet mechanism associated with one of said plates and operable by some moving part of the press for imparting rotation to the plates to assure proper distribution of 75 the ink thereon.

3. An attachment for printing presses embodying a supporting member, a plurality of ink plates positioned in eschelon with respect to the path of the form roller of the 80 associated press and mounted on the supporting member for rotation on fixed axes so as to form a support for said form roller during its entire travel over the plates in succession, means associated with the supporting member for rigidly mounting it on a printing press in place of the single plate ordinarily employed thereon, and means for rotating the ink plates on their fixed axes 85 while the supporting member remains stationary.

In testimony whereof, I have signed my name to this specification.

LOUIS FRIEDMAN.
